UNITED STATES PATENT OFFICE.

GEORGE H. ENNIS, OF LONG BEACH, CALIFORNIA.

DOSE DISTRIBUTOR.

Application filed January 15, 1927. Serial No. 161,329.

My invention relates to the testing of an oil well to determine the location of the water sands so that they may be sealed off, and it relates particularly to an apparatus 5 for depositing a dose of testing liquid in the body of liquid in the well, in the zone of the water sands.

It is highly important in the oil producing industry, that all water bearing sands be 10 sealed from the well so that the oil will not be mixed with the water and be reduced in commercial value. The water sands are very often difficult to locate.

In my application for Letters Patent— 15 method of and apparatus for determining water strata in wells, Serial No. 80,160, filed January 9, 1926, I describe a method of locating the water sands by distributing an electrolyte in the well and then bailing out 20 some of the liquid in the well so that the level will be lowered thus causing water to flow into the well from the water sands. A pair of spaced electrodes forming a primary battery is connected in an external 25 electric circuit and is then lowered into the well and the flow of current produced by the electrochemical action of the electrolyte on the electrodes is noted. When a noticeable change in flow occurs, it will be known that 30 the electrodes have passed out of the electrolyte or into a different electrolyte.

It is an object of this invention to provide a dose distributor for depositing a charge of liquid in a well at a desired depth.

It is another object to provide a dose distributor which can be lowered in a well and operated to discharge a treating liquid at any depth.

A further object of my invention is to provide a dose distributor in which the discharge means is operated by a pressure of the liquid in which the dose distributor is submerged, this pressure being set up by a movement of the dose distributor through 40 the liquid in a given direction.

It is another object of this invention to provide a dose distributor of this character which is operated so as to be capable of discharge by "jerking" it.

Yet another object of my invention is to provide a dose distributor in which a discharge means is controlled by a valve operated by pressure of the liquid in which the distributor is immersed, and in which the valve, once operated, automatically remains 55 open.

Further objects and advantages will be made manifest in the following description and in the accompanying drawings in which

Fig. 1 is a vertical sectional view of a preferred embodiment of my invention, showing its utility. 60

Fig. 2 is a horizontal sectional view taken on line 2—2 of Fig. 1.

Fig. 3 is a medial vertical sectional view 65 of the valve member of my invention.

Fig. 4 is a horizontal sectional view taken on the line 4—4 of Fig. 3.

Referring to Fig. 1, I show the lower end of a well 7 having a perforated casing 8 installed therein, the well being filled with a body of liquid 9. Water bearing sands are indicated at 10, the sands introducing water into the well unless they are properly sealed. 70

The dose distributor 14 has a tubular shell 75 15 closed at its lower end by a lower head 16, threadedly secured in the lower end thereof, and at its upper end by an upper head 17 threadedly secured to the upper end thereof.

The parts cooperate to provide a dose chamber 18. A vent pipe 20 threadedly received 80 in an opening 21 in the lower head 16, extends upwardly in the chamber 18, the upper end terminating slightly below the upper head 17. Centrally formed in the upper head 17 is a hole 22 which threadedly receives a pipe 23, this pipe being extended 85 downwardly in the chamber 18 to a position slightly above the lower head 16. The upper head 17 is provided with a bail 24 to which a cable 25 is connected for lowering the dose distributor 14 into and for raising it from the well 7.

Threadedly received in the upper end of the hole 22 is a nipple 26 which extends 90 above the top of the head 17 and is screwed into a threaded aperture 29 of a body 27 of a valve member 28. The body 27 has a central bore 30 which extends downwardly from the upper end to communicate with the hole 95 29. A threaded counter-bore 31 is formed in the bore 30 and a second counter-bore 32 is formed in the counter-bore 31 which has threads 33 formed in its upper end. An annular valve seat member 35 is threadedly 100 received into the counter-bore 31, the seat member 35 having a downwardly disposed valve seat 36 formed thereupon. Screwed into the threads 33 at the upper end of the counter-bore 32 is a spider 37 having a central opening 38 which is axially aligned with the valve seat 36.

105 110

6 A valve 40 has a head 41 which is adapted to seat against the seat 36 from which a stem 42 projects upwardly so as to be vertically guided within the opening 38 in the spider 37. An annular channel 43 is formed in the stem 42 as shown in Fig. 3. A compression spring 44 disposed about the stem 42 is compressed between the spider 37 and a washer 45 retained upon the upper end of 10 the stem 42 by a pin 46. The spring 44 thus sustains the valve 40 in its uppermost position, as shown in Fig. 3 in full lines, so that the valve head 41 is seated against the seat 36.

15 An externally threaded body 51 of a catch member 50 is received into a threaded opening 52 formed in the wall of the body 27 as shown in Fig. 4. The body 51 projects inwardly into the counter-bore 32 to a point 20 adjacent the valve stem 42. The body 51 has a bore 53 to receive a catch 54 which is adapted to project out of the mouth of the bore 53 and engage the surface of the valve stem 42. The catch 54 is retained 25 from leaving the bore 53 by a catch stem 56 which passes through a suitable opening provided in the body 51 between the bore 53 and the exterior thereof, the stem 56 having a head 57 provided upon its outer end. 30 A compression spring 59 is placed in the bore 53 to hold the catch 54 in extended position.

The operation of my invention is as follows:

35 The dose distributor is first filled with the testing liquid. This testing liquid is an electrolyte having marked electro-chemical characteristics. The dose distributor is then lowered into the well by means of the 40 cable 25, the valve 40 being closed at this time. As the dose distributor 14 moves downwardly into the liquid, a pressure of the liquid 12 against the cone-shaped lower head 16 is set up which tends to force the 45 water 12 upwardly through the pipe 20 in the chamber 18. The valve 40 being closed, however, the dose 65 is unable to flow upwardly out of the pipe 23 to make room for the admission of the water 12 upwardly 50 through the pipe 20 into the chamber 18. The dose distributor 14, therefore, passes downwardly throughout the length of the well without the admission of the water 12 into the chamber 18.

55 When the distributor reaches a depth where it is believed the water sands are, the dose of liquid is discharged. In Fig. 1, the distributor 14 is adjacent to the water sands 10 which is the proper place to discharge the dose. This is accomplished by a sudden jerking of the line 25 so as to raise the dose distributor 14 a short distance at an excessive rate of speed. A pressure of the water 12 upon the upper end of the dose distributor 14 is set up, this increased pressure being

applied to the upper face of the valve head 41. The spring 44 is sufficiently weak so that this increased pressure will force the valve 40 downwardly until the catch 54 lodges in the channel 43 and retains the 70 valve 40 in open position. After the lifting of the dose distributor 14 a short distance at an excessive rate of speed to accomplish the permanent opening of the valve 40, the dose distributor 14 is again 75 lowered at a uniform and predetermined rate of speed.

When the valve 40 is open as it is now the liquid will flow into the conical mouth 75 of the lower head 16, and the pipe 20 80 into the upper end of the chamber 18. This entrance of liquid displaces the dose 65 causing it to flow through the pipe 23, the passage 22, the nipple 17, and the valve member 28 into the well above the distributor. 85 The valve 41, together with its associated chambers and seat, comprises a fluid operated means permitting the dose to be displaced from the dose chamber by the fluid entering therein. The dose may also be discharged by raising the distributor. The dose distributor of my invention is made in different diameters and in each well treated, a distributor is selected having a diameter about a half inch or so less than the inside 90 diameter of the oil string. Thus when the distributor is raised suddenly an excessive pressure is applied to the top of the distributor causing the valve 40 to open. Also, due to the small space between the distributor, 100 and the wall of the oil string, an ample pressure is imposed upon the lower end of the distributor when this is lowered in the casing to force the contents of the distributor out of the upper end thereof. After distributing the dose the distributor is removed from the well, after which a test is made using the apparatus mentioned in the first part of the specification. If the test does not show up the water sands, another dose 110 is deposited in the well at another depth and another test is made; and so on until the water sands are found.

It is to be understood, of course, that when it is desired to re-use this distributor 115 in the manner above described, it may be recharged with a fresh dose 65 by pouring this fresh dose downwardly into the spider 37 so that it will flow downwardly through the tube 23 into the bottom of the chamber 120 18, rise in this chamber and displace the fluid already there, which fluid will be exhausted through the tube 20 out of the lower head 16. When the liquid having the qualities of the dose 65 begins to flow from the 12 lower head 16, it will then be known by the operator that the chamber 18 is entirely filled with the liquid of the dose. The head 57 of the catch stem 56 is then drawn outwardly to remove the catch 54 from the 13

channel 43 and permit the spring 44 to return the valve 40 to closed position. The dose distributor 14 is now ready for another dose distributing operation similar to the one just described.

From the foregoing description it is apparent that my invention is adapted for depositing a dose at a desired depth in a well, the distributor being lowered and then 10 jerked so as to open the valve 40.

While I have shown and described a definite embodiment of the present invention, it is to be understood that various changes may be made in this embodiment without 15 departing from the spirit of the invention or the scope of the appended claims.

I claim as my invention:

1. In a dose distributor of the class described, the combination of: walls forming 20 a dose chamber adapted to contain a dose; means connected to said dose chamber through which liquid may enter said dose chamber when said dose distributor is moved in a body of liquid in a well; means connected to said dose chamber through which 25 said dose passes from said dose chamber when displaced by said liquid; and means operated by jerking said dose distributor for permitting the entrance of said liquid into 30 said dose chamber.

2. In an apparatus of the class described, the combination of: a shell adapted to be submerged in a liquid, said shell being closed at its top and bottom to form a dose chamber, there being vent means communicating 35 between one end of said chamber and the exterior of said shell; means for conducting said liquid into the opposite end of said chamber when said shell is passed through 40 said liquid so as to cause said dose to flow out of said chamber through said vent means; and valve means for maintaining one of said other means closed, said valve means being operable to open one of said 45 other means.

3. In an apparatus of the class described, the combination of: a shell adapted to be submerged in a liquid, said shell being closed at its top and bottom to form a dose chamber, there being vent means communicating 50 between one end of said chamber and the exterior of said shell; means for conducting said liquid into the opposite end of said chamber when said shell is passed through 55 said liquid so as to cause said dose to flow out of said chamber through said vent means; and a valve for closing said conducting means.

4. In an apparatus of the class described, 60 the combination of: a shell adapted to be submerged in a liquid, said shell being closed at its top and bottom to form a dose chamber, there being vent means communicating between one end of said chamber and the 65 exterior of said shell; means for conduct-

ing said liquid into the opposite end of said chamber when said shell is passed through said liquid so as to cause said dose to flow out of said chamber through said vent means; and a valve for closing said conducting 70 means, said valve opening when said shell is passed through said liquid in a given direction.

5. In an apparatus of the class described, the combination of: a shell adapted to be 75 submerged in a liquid, said shell being closed at its top and bottom to form a dose chamber, there being vent means communicating between one end of said chamber and the exterior of said shell; means for conducting 80 said liquid into the opposite end of said chamber when said shell is passed through said liquid so as to cause said dose to flow out of said chamber through said vent means; and a valve for closing said 85 conducting means, said valve opening when said shell is passed through said liquid in a given direction at an excessive rate of speed.

6. In an apparatus of the class described, the combination of: a shell adapted to be 90 submerged in a liquid, said shell being closed at its top and bottom to form a dose chamber, there being vent means communicating between one end of said chamber and the exterior of said shell; means for conducting 95 said liquid into the opposite end of said chamber when said shell is passed through said liquid so as to cause said dose to flow out of said chamber through said vent means; a valve for closing said conducting 100 means, said valve opening when said shell is passed through said liquid in a given direction; and means for retaining said valve in open position.

7. In an apparatus of the class described, the combination of: a shell forming a dose chamber and adapted to be passed through a liquid, there being a vent means to permit the discharge of a dose from said chamber, and an inlet for admitting liquid into said 105 chamber in a manner to force said dose out of said vent; and a valve adapted to close said inlet.

8. In an apparatus of the class described, the combination of: a shell forming a dose chamber and adapted to be passed through a liquid, there being a vent means to permit the discharge of a dose from said chamber, and an inlet for admitting liquid into said 110 chamber in a manner to force said dose out of said vent; a valve adapted to close said inlet; and resilient means for holding said valve in closed position.

9. In an apparatus of the class described, the combination of: a shell forming a dose chamber and adapted to be passed through a liquid, there being a vent means to permit the discharge of a dose from said chamber, and an inlet for admitting liquid into said 115 chamber in a manner to force said dose out 120 of said vent; a valve adapted to close said inlet; and resilient means for holding said valve in closed position.

125

of said vent; a valve adapted to close said inlet; and resilient means for holding said valve in closed position, said valve being adapted to be opened against said resilient means by liquid pressure set up by movement of said shell through said liquid in a given direction.

10. In an apparatus of the class described, the combination of: a shell forming a dose chamber and adapted to be passed through a liquid, there being a vent means to permit the discharge of a dose from said chamber, and an inlet for admitting liquid into said

chamber in a manner to force said dose out of said vent; a valve adapted to close 15 said inlet; resilient means for holding said valve in closed position, said valve being adapted to be opened against said resilient means by liquid pressure set up by movement of said shell through said liquid in a given 20 direction; and means for holding said valve in open position.

In testimony whereof, I have hereunto set my hand at Long Beach, California, this 18th day of December, 1926.

GEORGE H. ENNIS.
